DESIGN.

—o—

R. F. SCHERMERHORN & F. S. WELLER.
COOKING RANGE.

No. 18,254.

Patented Apr. 10, 1888.

UNITED STATES PATENT OFFICE.

RODNEY F. SCHERMERHORN AND FERDINAND S. WELLER, OF QUINCY,
ILLINOIS, ASSIGNEES TO THE CHANNON, EMERY STOVE COMPANY,
OF SAME PLACE.

DESIGN FOR A COOKING-RANGE.

SPECIFICATION forming part of Design No. 18,254, dated April 10, 1888.

Application filed January 12, 1888. Serial No. 260,583. Term of patent 7 years.

To all whom it may concern:

Be it known that we, RODNEY F. SCHERMERHORN and FERDINAND S. WELLER, both citizens of the United States, residing at 5 Quincy, county of Adams, State of Illinois, have invented and produced a new and original Design for a Cooking-Range, of which the following is a specification, reference being had to the accompanying engraving, forming 10 a part thereof.

This design embraces several new and distinctive parts and combinations of parts which go to make up the whole design, as herein-after specified.

15 One integral part of this design is the shape and ornamentation of the right and left lower hot-closet doors, A and B, which ornamentation is alike on each, and consists on the right-hand door, A, of a broad horizontal spray of foliage, a, displayed on a rough ground and extending from near the outside of said door A to the inside edge thereof, the inner end flaring somewhat upward and downward, the horizontal part of said spray inclosed above 20 and below and on its outer end by a raised right line, and outside said raised right line, at the outer end of said door A, of like width and direction with said spray, appears a series of short raised parallel lines, b, to the outside edge 25 of said door. From the outside edge of said door, adjacent to and one row, c, above and another row, c', below said series and spray, extends a row of projecting flat scallops or large beads, the one c beginning to curl or turn 30 spirally after traversing about three-quarters of the face of said oven-door, starting with a downward turn, but said curl or spiral turning part of said row c being mainly above the line of the horizontal part or residue of said 35 row c, while the lower row, c', is disposed correspondently, all as shown.

40 A further distinctive part of this design is the shape and ornamentation of the reservoir end C, which ornamentation consists of a single slightly-curving willow branch, d, at the inside lower corner of the face of said reservoir end C, disposed nearly diagonally thereupon and demarcated from the residue thereof by a plain intaglio line parallel to said branch

45 d. In the center of the lower part of said reservoir end C is an intaglio line or tracing, e, in spiral form. The main part of said reservoir end C is occupied by a bold raised rectangular panel, on the face whereof appears near the lower part of said panel a horizontal 50 ornamental branch or spray of leaves, f, displayed on a rough ground, extending nearly across the same, inclosed by four plain raised lines in rectangle. At the left end of said rectangle, of like width and direction with said 55 rectangle, is a series of short plain raised parallel right lines, g, extending to the left edge of said panel, while across the face of said panel, adjacent to said rectangle and series of parallel lines, one row, h, above and another row, h', below said rectangle and series, extends a straight row of projecting flat scallops or large 60 beads. On the upper part of said panel—its base adjacent to the upper row of scallops or beads—appears a pyramidal decoration, i, consisting of a cactus plant in flower and leaf. On the inside border of said reservoir end C is a slender vertical spray of leaves, j, extending 65 from bottom to top of said border, all as shown.

70 Another distinctive part of this design is the shape and ornamentation of the oven-door D, which ornamentation consists of a horizontal plait or stripe of foliage, k, displayed on a rough ground and extended across the lower 75 part of said last-named door, D, from the right edge thereof to the door-knob, inclosed by a plain raised line. Parallel with and adjacent to said last-described line throughout its course 80 extends a row of projecting flat scallops or 85 beads, l. Adjacent to and above said last-described row of scallops or beads, on either side of the center and upper part of said oven-door D, one upon the right hand, and another on the left hand thereof, appear large ornamental 90 sprays n and n', so disposed as to nearly meet at the top, and leaving an approximately circular central space inclosed by said last-described sprays and the decoration of said oven-door D, hereinbefore described, all as shown. 95

Another distinctive part of said design is the shape and ornamentation of the upper hot-closet doors, E and F, which ornamentation is

- in general the same in design with that upon the lower hot-closet doors, A and B, respectively, and hereinbefore described, but is on a reduced scale, all as shown.
- 5 Another distinctive part of this design is the shape and ornamentation of the cresting G, which ornamentation consists of a succession of open triangles, o, having straight bases and curved sides, displayed within which triangles is a conventional flower-and-leaf design, p, and between said triangles is an upright member showing a bead near the top thereof, while at either end of said row of triangles, and extending to either end of said cresting, is exhibited an amorphous compound outline configuration, q and q', having a rosette at its lower outer corner. The top of said cresting G is finished with a line of inverted semicircles, r, all as shown.
- 10 Another distinctive part of this design is the shape and ornamentation of the upper hot-closet end, H, which ornamentation consists of an upright oak branch, s, displayed upon the plane face thereof, all as shown.
- 15 Another distinctive part of this design is the shape and ornamentation of the support or upright bracket I, which carries the upper hot-closet, which ornamentation consists of a part of vertical branches with trilobate leaves t, one branch upright, the other inverted, displayed in the center of the front of said support I, inclosed by a plain raised circle, said circle inclosed by two horizontal and two vertical plain raised reversed arcs, while in each spherical triangle formed by said horizontal arcs, vertical arcs, and inclosed circle is shown a small rosette. On either side of said last-described branches, at the front angles of said support I, extending from top to bottom of said support, is a plain vertical raised line crossed at right angles near each extremity by a plain horizontal raised line extending across the front of said bracket I, and on the space demarcated by said lines, below the lower horizontal line and between the vertical lines, appear a conventional rose branch and blooms, u, while in the space demarcated by said lines above the upper horizontal line and between the vertical lines are shown 20 a conventional rose branch and bloom, u'. At the back of said bracket I and at the termini of the last-described horizontal lines is a vertical row of beads, v, from top to bottom of said bracket, and next outwardly from said row of beads is a row of trefoils, w, and next outwardly therefrom is ornamental screen or scroll work having in the center an isosceles right-angled triangle, x; above said triangle are suspended in scroll-work two small 25 rosettes, and below the said triangle is suspended in scroll-work a conventional leaf or foliage exhibit, y, and two rosettes, said screen or scroll work being of an open character, all as shown.
- Another distinctive part of this design is the shape and ornamentation of the side fire-door, J, which ornamentation is in general similar in design with that upon the panel on the reservoir end C, hereinbefore described, all as shown.
- Another distinctive part of this design is the shape and ornamentation of the ash-box end K, which ornamentation consists in general of like features with the ornamentation upon the panel on the reservoir end C, hereinbefore described, but is on a reduced scale, all as shown.
- We claim as new—
1. In a design for a cooking-range herein shown and described, the design for lower and upper hot-closet doors, consisting of the branch a, the series of parallel lines b, the row of beads or scallops c, and the row of beads or scallops c'.
  2. In a design for a cooking-range herein shown and described, the design for a reservoir-panel, side fire-door, and ash-box end, consisting of the branch d, the spiral line e, the spray f, the series of horizontal lines g, the rows of beads or scallops h and h', the cactus ornament i, and the spray j.
  3. In a design for a cooking-range, the design for an oven-door herein shown and described, consisting of the foliage k, the line of beads or projecting scallops l, and the branches n and n'.
  4. In a design for a cooking-range, the design for a cresting or finish for the upper hot-closet herein shown and described, consisting of the triangles o, the upright members p intervening the compound amorphous figures q and q', and the row of semicircles r.
  5. In a design for a cooking-range, the design for an upper hot-closet panel herein shown and described, consisting of the oak branch s.
  6. In a design for a cooking-range, the design for a support or bracket for an upper hot-closet herein shown and described, consisting of the branches t, the sprays u and u', the row of beads v, the row of trefoils w, the isosceles triangle x, and the foliage y.
  7. In a design for a cooking-range, the whole design unitarily, embracing design for the lower hot-closet doors, the reservoir end, the oven-door, the upper hot-closet doors, the cresting or finish of the upper hot-closet, the upper hot-closet end, the bracket or support for the upper hot-closet, the end fire-door, and the ash-box end, all substantially as herein shown and described.

RODNEY F. SCHERMERHORN.
FERDINAND S. WELLER.
